(57) **CLAIM**

The ornamental design for a plant growth lamp, as shown and described.

DESCRIPTION

FIG. 1 is a first perspective view of a plant growth lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the plant growth lamp thereof;

FIG. 10 is an enlarged view of the selected portion 10 in FIG. 1;

FIG. 11 is an enlarged view of the selected portion 11 in FIG. 1;

FIG. 12 is an enlarged view of the selected portion 12 in FIG. 2;

FIG. 13 is an enlarged view of the selected portion 13 in FIG. 2;

FIG. 14 is an enlarged view of the selected portion 14 in FIG. 2; and,

FIG. 15 is an enlarged view of the selected portion 15 in FIG. 9.

The broken lines shown in the drawings depict portions of the plant growth lamp that form no part of the claimed design.

1 Claim, 15 Drawing Sheets
